AMUSEMENT DEVICE

Raymond H. Frisbie, Kewaunee, and William Wright, Green Bay, Wis.

Application June 25, 1931. Serial No. 546,698

2 Claims. (Cl. 272—33)

This invention relates to improvements in amusement devices.

One of the objects of the present invention is the provision of a toy amusement device in the form of a mechanically operated merry-go-round, which is designed to not only provide amusement for children, but to provide a new exercising device as well, and one which can be set up in a comparatively small space and operated by children.

Another object of the present invention is the provision of an amusement device which includes a circular trackway with traction supported carriages, the wheels of which are guided by the trackways, together with means operated from the carriages for manually propelling the same around the trackway, whereby the device not only provides an amusement device in the form of a merry-go-round, but includes means in the form of an exercising device for the rider of the carriages.

A further object of the present invention is the provision of a novel amusement device in the form of a merry-go-round including a circular trackway with carriages adapted to ride within said trackway and a central stationary gear co-operating with suitable pinions on the inner ends of shafts which are manually rotated by the operators of the carriages about the circular trackway.

With the above and other objects in view, the invention consists in the novel features of construction, the combination and arrangement of parts hereinafter more fully set forth, pointed out in the claims and shown in the accompanying drawings wherein:

Figure 1 is a top plan view of an amusement device, constructed in accordance with our invention, with parts broken away and illustrated in cross section;

Figure 2 is a sectional view on the line 2—2 of Figure 1; and

Figure 3 is a side elevation of one of the carriages.

Referring more particularly to the drawings, 1 indicates a circular channel trackway supported upon the outer ends of radially disposed supporting ties 2, the inner ends of which are arranged in meeting relation, as illustrated in Figure 1, and are connected by means of a base plate 3. Mounted within the central portion of the base plate 3 is an upright shaft 4 having a hub 5 and supported upon the hub 5 is a circular bevel gear 6 arranged in spaced relation with the base

plate 3 and connected thereto by means of supporting posts 7.

The carriages used in connection with the trackway 1 include the seat platform 8 having brackets 9 at each end thereof carrying shafts 10 upon which the traction wheels 11 are mounted. These traction wheels are preferably provided with tires 12 which may be of rubber or other resilient material to provide a smooth running of the carriages in the trackway.

The carriages are preferably connected by means of a cross beam 13 rotatably mounted upon the upright shaft 4 and supported upon the collar 14 carried by said shaft. The ends of the cross bar 13 are connected directly to the carriages on the lower face of the platforms 8. Supported within suitable bearings 15 beneath the cross bar 13 are the drive shafts 16, the inner ends of which carry bevel pinions 17 co-operating with the circular bevel gear 6.

The outer ends of the shafts 16 are provided with crank portions 18 which are connected to the operating yokes 19 rockably mounted upon the platforms 8.

The operating yokes 19 are preferably of U-shaped construction, as shown in Figure 2, with the upper loop portion forming the handle for the operator and the side portions are connected by means of a cross piece 20 which is rotatably mounted in a bearing loop 21 attached to the under face of the platform of the carriage. A cross piece 22 connects the lower arms of the yoke 19 and pivotally connected to the cross piece 22 is a link 23, the other end of which is pivotally connected to the crank 18 at the outer end of each shaft 16.

From the above construction, it will be apparent that by rocking the upper loop portion 24 of the yoke 19 on each carriage, movement will be imparted to the shaft 16, causing the pinions 17 to travel around the circular bevel gear 6 which in turn will urge the carriages around the trackway 1.

While we have described and illustrated only one cross bar 13 and two carriages attached to the same, it will be apparent that another cross bar could be arranged transversely of the one illustrated and the device used with four carriages if the occasion should require.

In fact the device could be made large enough so that a number of cross bars could be used, all integrally connected at the central portion, thus providing for the use of several carriages.

It will be apparent from the foregoing that we have provided a very simple and inexpensive

device of this character which will afford considerable amusement for children and at the same time, due to the necessary manipulation of the yoke 19, the children occupying the carriages 8 will be benefited by the exercise necessary for the operation of the carriages. Thus, the device is not only an amusement device, but one which provides beneficial exercise to children.

10 The construction of the same is of a very simple nature, so that it can be placed on the market at a very low cost.

Attention is directed to the fact that the lower ends of the U-shaped yoke 19 are extended laterally to form suitable foot rests 25, whereby the child or party using the carriage can place their feet upon the rests 25 and in operating the yoke 19 pressure can be applied to these foot rests as well as the application of power to the upper end of the yoke for using both the feet and the hands for operating the carriages.

This construction creates a beneficial exercise in that in operating the carriages, the entire body is in motion.

25 We have shown and described the preferred embodiment of our invention, it will be apparent from the foregoing that slight changes may be made in the construction when putting the invention into practice without departing from the spirit of the same or the scope of the appended claims.

We claim:

1. An amusement device comprising a plurality of radiating ties, a circular track secured

to the ends of the ties, an axially disposed disc-shaped base plate secured to and connecting said ties together, a rigid supporting shaft secured to the axial center of the base plate, a beveled gear secured to the shaft, reinforcing rods connecting the gear to the base plate, a supporting collar secured to the shaft, a rotatable head mounted on the shaft resting on the collar, radially extending supporting arms secured to the head, carriages connected with the arms having supporting wheels mounted in the track, operating shafts rotatably carried by the supporting arms, means for operating the shafts from the carriages, and pinions connected to the inner ends of the operating shafts meshing with said bevel gear.

2. An amusement device comprising a supporting shaft, a beveled gear on the supporting shaft, a rotatable head mounted on the shaft above the beveled gear, radially extending arms secured to the head and rotatable therewith, operating shafts rotatably supported by the arms, pinions secured to the inner ends of the shafts meshing with the beveled gear, carriages secured to the outer ends of the arms, inverted U-shaped operating handles pivotally connected to the carriages and straddling the seat portions thereof, outwardly extending feet formed on the lower ends of the handles, operating cranks on the outer ends of the shafts, and links operatively connecting the cranks to the handles.
